(57) **CLAIM**

The ornamental design for the mecca finder apparatus, as shown and described.

DESCRIPTION

FIG. 1 is a top right perspective view of the mecca finder apparatus according to the present invention with the Middle East Map installed on the compass;

FIG. 2 is a top plan view of the mecca finder apparatus according to FIG. 1;

FIG. 3 is a side elevational view of the mecca finder apparatus according FIG. 1;

FIG. 4 is a cross-sectional view taken on line 4—4 of FIG. 2;
FIG. 5 and 6 are top plan views of the mecca finder apparatus with no map installed on the compass and with the world map installed on the compass; and,

FIG. 7 is an exploded perspective of the mecca finder apparatus according to FIG. 1.

The broken line showing of features are included for the purpose of illustrating non-claimed subject matter and forms no part of the claimed design.
